Primary Examiner — Austin Murphy(74) *Attorney, Agent, or Firm* — Michele V. Frank;
Venable LLP(57) **CLAIM**

The ornamental design for a base for a vaginal device, as shown and described.

DESCRIPTION

FIG. 1 is an upper perspective view of an opaque version of a base for a vaginal device in accordance with the new design.

FIG. 2 is a front elevational view thereof.

FIG. 3 is a right side elevational view thereof.

FIG. 4 is a rear elevational view thereof.

FIG. 5 is a left side elevational view thereof.

FIG. 6 is a top plan view thereof.

FIG. 7 is a bottom plan view thereof.

FIG. 8 is an upper perspective view of a transparent or translucent version of a base for a vaginal device in accordance with the new design.

FIG. 9 is a front elevational view thereof.

FIG. 10 is a right side elevational view thereof.

FIG. 11 is a rear elevational view thereof.

FIG. 12 is a left side elevational view thereof.

FIG. 13 is a top plan view thereof; and,

FIG. 14 is a bottom plan view thereof.

The broken lines in FIGS. 1-14 illustrate portions of the base for a vaginal device that form no part of the claimed design.

1 Claim, 10 Drawing Sheets(56)
